ELECTRODYNAMIC RECORDING DEVICE

Holger Christian Arentzen, Copenhagen,
DenmarkApplication January 10, 1948, Serial No. 1,624
In Denmark January 11, 1947

9 Claims. (Cl. 179—100.41)

1

This invention relates to electrodynamic recording devices, particularly phonograph recording devices.

It has been heretofore proposed to provide the moving systems of recording devices with a feed-back coil for generating an E. M. F. varying in accordance with the mechanical oscillations of the system and adapted to compensate for distortions in the recording when fed back to the input side thereof.

Such feedback systems, however, have so far been confined to recording devices of the so called "hill-and-dale" type, in which the recording stylus vibrates in a vertical plane.

It is an object of the present invention to provide means, in an electrodynamic recording device of the negative feedback type capable of cutting phonograph records of the conventional type having laterally cut grooves and providing for lateral movements of the reproducing stylus in the pick-up.

Another object of the invention is to provide means affording placing of the feedback coil in an advantageous position relatively to the stylus and the driving coil for the oscillatory system so as to increase the efficiency of the feedback coil.

A still further object of the invention is to provide means facilitating improved mounting of the oscillatory system including the driving coil, the feedback coil and the stylus, in the fixed structure of the recording device.

These and other objects and features of the invention will be more clearly understood from the following detailed description and the accompanying drawings in which:

Fig. 1 is a sectional front view of a recording device according to the invention.

Fig. 2 is an enlarged bottom plan view of the pole system.

Fig. 3 is an enlarged elevation of the support member for the oscillatory system.

Fig. 4 is a section taken along the line 4—4 in Fig. 3.

Referring to Fig. 1 numeral 2 designates a pair of permanent magnets disposed within the housing 1 and having pole pieces 3. 4 is a cylindrical core of soft iron or other ferro-magnetic material disposed between the pole pieces 3 and defining two substantially vertical air-gaps 5.

6 are secondary pole pieces associated with the magnets 2 and disposed above an annular body or bridging member 7 of soft iron or another ferro-magnetic material so as to form two substantially horizontal air-gaps 8 therebetween.

2

The stiff funnel-shaped member 9 comprises an upper cylindrical portion 9a on which the driving coil 10 is mounted the member 9 terminating in a conical portion 9b having a tubular extension 9c on which the driven coil 11 is mounted. A holder 12 for the stylus 13 is fitted at the lower end of the extension 9c. The upper end of the tubular extension 9c adjacent the conical portion 9b is provided with inner threads 14 adapted to receive a threaded member 15 (Fig. 3) on a support for mounting the oscillatory system in the housing 1.

As shown more clearly in Figs. 3 and 4 the support for the oscillatory system comprises a main conical body 16 in which a pair of parallel linear grooves or slots 17 have been cut so as to divide the main body 16 into two conical discs, 16a and 16b connected by and defining the thin strip 18 formed between the slots. This strip 18 constitutes a resilient blade member providing a substantially horizontal pivotal axis, as well as an axis of rotation for the lower part (disc 16a) of the supporting member which is affixed in the oscillatory system relatively to the upper part (disc 16b) which by means of a threaded extension 19 is affixed to a member, such as a flange 20 of brass or another non-ferrous metal within the housing 1. The support 16 is preferably made of beryllium-copper or Phosphor bronze whereby adequate mechanical strength and flexibility of the resilient or spring leaf strip 18 is achieved. This design has the structural advantage of extreme simplicity and greatly facilitates the correct and reliable centering of the oscillatory system relatively to the air-gaps.

21 is a copper ring disposed between the pole pieces 2 and 3 so as to constitute a magnetic shield between the driving coil 10 and the feed-back coil 11.

As shown in Fig. 1 the feedback coil 11 is shaped as a flat disc which is mounted on the tubular extension 9c adjacent the holder 12 for the stylus 13. This construction not only facilitates the mounting and dismounting of the feedback coil but also provides for increased efficiency of this coil owing to the fact that the width of the airgaps 8 may thereby be substantially decreased so as to ensure a high flux density between the pole pieces 3 and the ring 21. A further advantage of this construction resides in the fact that the substantially lateral movement of the coil 11 in the horizontal airgaps 8 can be made relatively large without incurring any risk of fouling.

The disposition of the driving coil 10 in the substantially vertical and annular airgaps 5 and

of the driven or feedback coil 11 in the substantially horizontal airgaps 8 at either side of the axis of rotation enables the whole oscillatory system to be built up of simple and solid elements while simultaneously providing for convenient and efficient mounting of this system by means of the supporting member 16 comprising the resilient strip 18.

Having thus described the invention, what is claimed as new and desired to be secured by Letters Patent, is:

1. In an electrodynamic recording device; a primary magnetic circuit defining two vertical air gaps, a secondary magnetic circuit defining two horizontal air gaps, an oscillatory system adapted to support a stylus and including a driving coil disposed in the vertical air gaps, a feedback coil disposed in the horizontal air gaps, and means for providing a substantially horizontal pivotal axis for said oscillatory system intermediate said vertical and horizontal air gaps.

2. In an electrodynamic recording device; a magnetic circuit defining two vertical and two horizontal air gaps, an oscillatory system including a stylus and a driving coil disposed to extend in said vertical air gaps, a feedback coil disposed in said horizontal air gaps, and means forming a substantially horizontal pivotal axis, said pivotal axis substantially coinciding with the center of gravity of said oscillatory system.

3. An electrodynamic recording device comprising a magnetic structure including two vertical and two horizontal air gaps, an oscillatory system including a stylus and holder therefor, a driving coil disposed on said holder and in said vertical air gaps and a feedback coil disposed on said holder and in said horizontal air gaps, a member supporting said oscillatory system in said magnetic structure and comprising a conical body provided with a pair of grooves extending through said body and defining a resilient strip between two conical portions of said body, and fastening means at either end of said conical body to facilitate connection of said holder with said conical body and of said conical body with said magnetic structure, respectively.

4. In an electrodynamic recording device; a magnetic structure, an oscillatory system including spaced apart vertical and horizontal air gaps, and supporting means for said oscillatory system and including a holder for a stylus, said supporting means comprising a conical body, said body being provided with two conical discs connected with each other by a relatively short resilient strip therebetween, and fastening means at either end of said conical body to facilitate connection of the latter to said magnetic structure and to said stylus holder, respectively, said resilient strip being disposed at a location between said vertical and horizontal air gaps.

5. In an electrodynamic recording device; a magnetic structure, an oscillatory system, and supporting means for said oscillatory system, said supporting means comprising a conical body, a pair of grooves provided in said body and defining therebetween a relatively short resilient strip, and a threaded extension at either end of said body to facilitate fastening of said conical body to said structure and connection with a stylus, respectively.

6. An electrodynamic recording device comprising a housing, a magnet within said housing, a first pair of pole pieces, an annular core of ferromagnetic material intermediate said first pair of pole pieces so arranged as to form two sub-

stantially vertical airgaps between said pole pieces and said core, a second pair of pole pieces and an annular body of ferromagnetic material so arranged as to form two substantially horizontal air gaps between said second pair of pole pieces and said annular body, an oscillatory system comprising a driving coil disposed in the vertical air gaps and a driven coil disposed in the horizontal air gaps, a holder member for said coils, a support extending into said member and affixed with one end therein and with the other end to a portion of said housing, said support comprising a resilient strip adapted to provide a substantially horizontal pivotal axis for said oscillatory system and being disposed at a level intermediate the levels at which said driving and driven coils are arranged, said strip forming a spring leaf which is substantially stiff and inflexible in all directions except against vibratory movements around said pivotal axis.

7. An electrodynamic recording device comprising a ferromagnetic core member including a cylindrical portion having a longitudinal axis, a pair of primary magnetic pole pieces of opposite polarity disposed at opposite sides of said core member and defining two substantially vertical air gaps lengthwise of said core member between it and said primary pole pieces, a pair of secondary magnetic pole pieces axially spaced from said primary magnetic pole pieces and terminating in substantially flat pole faces positioned adjacent said longitudinal axis, a ferromagnetic bridging member having surface portions facing said flat pole faces of said secondary pole pieces so as to define two substantially horizontal air gaps between said surface portions of said bridging member and said flat pole faces, and an oscillatory system mounted for pivotal movement about an axis extending between said primary and secondary pole pieces and perpendicularly to said longitudinal axis, said oscillatory system being adapted to carry a stylus, a driving coil surrounding said cylindrical portion of said core member so as to extend through said substantially vertical air gaps on both sides of said core member, and a feedback coil located in said substantially horizontal air gaps between said secondary pole pieces and said bridging member.

8. An electromagnetic recording device having an axis; comprising magnetic circuit means defining two substantially vertical air gaps in symmetrical positions with respect to a vertical plane and disposed in series in the magnetic path, and further defining two substantially horizontal air gaps in similar symmetrical positions with respect to said axis, said horizontal air gaps being axially spaced from said vertical air gaps and being likewise disposed in series in the magnetic path, and an oscillatory system mounted for pivotal movement about a horizontal axis in said plane of symmetry and intermediate of said vertical and horizontal air gaps, said oscillatory system including a stylus, a driving coil arranged to extend within said substantially vertical air gaps, and a feedback coil arranged to extend within said substantially horizontal air gaps.

9. In an electrodynamic recording device; a magnetic structure including spaced apart vertical and horizontal air gaps, an oscillatory system including a holder for a stylus, and supporting means for said oscillatory system comprising two conical disks connected with each other by a resilient strip therebetween, and fastening means at either end of said supporting means to facilitate connection of the latter to said magnetic

structure and to said stylus holder, respectively, said resilient strip being disposed at a location between said vertical and horizontal air gaps.
